UNITED STATES PATENT OFFICE.

ALEXANDER M. SUTHERLAND, OF NEW YORK, N. Y.

GAS-RETORT.

SPECIFICATION forming part of Letters Patent No. 449,142, dated March 31, 1891.

Application filed August 9, 1889. Serial No. 320,290. (No model.)

To all whom it may concern:

Be it known that I, ALEXANDER M. SUTHERLAND, a subject of the Queen of Great Britain, and a resident of New York, in the county and 5 State of New York, have invented a new and useful Improvement in Gas-Retorts, of which the following is a specification.

This invention relates to the manufacture of gas.

10 The object of the invention is to produce a retort of such construction that by its use hydrocarbons may be transformed into a fixed gas without carbonizing or burning any appreciable portions of them.

15 With this object in view the invention consists in a retort having a main inlet or receiving tube, a commingling-chamber, and a series of tubes of any desired size, preferably smaller in diameter than that of the inlet tube, connected with the commingling-chamber and designed to convey the hydrocarbons back to a stand-pipe or outlet, through which the gas is conveyed to a gasometer or the like.

20 I have illustrated my invention in the accompanying drawings, in which—

Figure 1 is a perspective view of my improved retort. Fig. 2 is a sectional view thereof, showing the spiral rib for causing the hydrocarbons passing through the tubes to impinge against the sides of the tubes; and Fig. 30 3 is a sectional view of the rear of the retort, showing the commingling-chamber.

In the drawings, A represents the exterior of the retort, which is preferably of fire-clay 35 enameled inside and outside.

At a suitable place in the retort, preferably near the bottom, is an inlet-tube B, through which hydrocarbons to be converted are introduced. The inlet-tube leads through the retort to the rear thereof, where it communicates with the commingling-chamber C. The rear face of this chamber is formed by the removable plate D, which allows access to the rear ends of the tubes for the purpose of re-

40 moving or cleaning or for removing any obstruction therefrom when desired. The stock after being carried into the commingling-chamber enters the small pipes E, and by them is carried to the front of the retort, from 45 whence, being then in the form of a fixed gas, it is conveyed to suitable gasometers or the like.

The tubes E, through which the gas is carried from the commingling-chamber to the front of the retort, are preferably, though not necessarily, of a smaller diameter than those of the inlet-tube.

In gas-making apparatus as generally constructed the hydrocarbons employed are subjected to excessive heat in retorts during the process of fixing, resulting in the burning and destruction of a large portion of the carbonaceous substances contained. In my improved retort I avoid this difficulty and produce a fixed gas by causing the stock to impinge against a maximum amount of surface heated to a moderate temperature. To accomplish this, I provide each of the tubes through which the gas is passed in the fixing process with an internal spiral rib F of such construction that as the gas passes through the tubes it is continually revolved and dashed against the sides of the tubes, resulting in the thorough decomposition of the hydrocarbon and insuring its contact with the maximum amount of fixing-surface. The spiral rib is preferably twisted throughout its entire length in a uniform direction.

Having thus fully described my invention, what I claim as new, and desire to secure by Letters Patent, is—

1. In an apparatus for manufacturing gas, the retort consisting of an inlet-tube, a commingling-chamber, and two or more outlet-tubes arranged substantially parallel with the inlet-tube, whereby the vapor is introduced through the inlet-pipe, commingled in a chamber, and returned through a number of pipes, and thereby brought into contact with a large amount of surface to insure fixing, substantially as described.

2. In apparatus for manufacturing gas, the retort consisting of the inlet-pipe, the commingling-chamber, and the outlet-tubes arranged substantially parallel with the inlet-tube and smaller in diameter than the inlet-tube, all the tubes having spiral ribs placed therein, substantially as described.

3. In apparatus for manufacturing gas, the retort consisting of the inlet-tube, the commingling-chamber, the outlet-tubes of smaller diameter than the inlet-tube and arranged substantially parallel with the inlet-tube, and spiral ribs having a continuous twist through-

out placed in the tubes, substantially as described.

4. In apparatus for the manufacture of gas, the retort consisting of the inlet-tube, the commingling-chamber having the removable end, and the return-tubes of smaller diameter than the inlet-tube and arranged substantially parallel with the inlet-tube, substantially as described.

In testimony that I claim the foregoing as my invention I have signed my name in presence of two witnesses this 30th day of July, 1889.

ALEXANDER M. SUTHERLAND.
